Primary Examiner — T. Chase Nelson*Assistant Examiner* — Mark Cavana(74) *Attorney, Agent, or Firm* — Cantor Colburn LLP(57) **CLAIM**

The ornamental design for a smart band, as shown and described.

DESCRIPTION

FIG. 1 is a perspective view of a smart band, showing our new design;

FIG. 2 is a front view thereof;

FIG. 3 is a rear view thereof;

FIG. 4 is a side view thereof;

FIG. 5 is another side view thereof;

FIG. 6 is a top plan view thereof; and,

FIG. 7 is a bottom plan view thereof.

The broken lines are for environmental purpose only and form no part of the claimed design.

The shade lines in the figures show contour and not surface ornamentation.
